UNITED STATES PATENT OFFICE.

MAXIMILIEN MARIS, OF CHICAGO, ILLINOIS.

GAME.

1,138,233.

Specification of Letters Patent.

Patented May 4, 1915.

Application filed January 25, 1915. Serial No. 4,087.

To all whom it may concern:

Be it known that I, MAXIMILIEN MARIS, a citizen of the United States, residing at Chicago, in the county of Cook and State 5 of Illinois, have invented a certain new and Improved Game, of which the following is a description.

My invention relates to game apparatus embodying a plurality of variously marked 10 pieces consisting of blocks, cards, or the like, used in conjunction with a prepared game board of improved construction, and the primary object of the invention is to provide a new and improved game apparatus 15 which may be adapted for use in playing a variety of games.

A further object is to provide an improved form of game apparatus especially adapted for the amusement and recreation 20 of adults, as the game may be developed to require as high a degree of skill as is required, for example, in playing the familiar games of chess or checkers, although the invention adapts itself well for the amusement 25 and recreation of children.

For the attainment of these ends and to accomplish certain other new and useful objects which will appear, the invention consists in the construction, combination, and 30 arrangement of the several parts of the game board and playing pieces as hereinafter more fully described and claimed, and as shown in the accompanying drawings illustrating the preferred embodiment of the in- 35 vention.

In the said drawings, Figure 1 is a top plan view of the essential designations of the game board; and Figs. 2 to 5 inclusive illustrate classes of game pieces and the 40 manner of marking them.

The markings indicating the essential features of the top of the game board shown in Fig. 1 may be applied to a board of any desired construction, the board itself not being herein shown. The outline of the marked portion of the board shown in Fig. 1 is preferably square in form as indicated by the marginal lines 10 of the drawing, these lines 10 marking the outer boundaries 45 of the game portion of the board which is divided by four intermediate spaced parallel lines designated by the reference character 11, into twenty-five squares of equal size, since the lines 11 are all parallel and one 50 set of four intermediate lines extends at right angles to the other set of four inter-

mediate lines and both sets are parallel with the outer boundary lines 10. In the embodiment of the game board herein illustrated, the right lines 10 and 11 are in black in contrast to the general field color of the board, and the color of the square is bounded by the lines 10 and 11. At the intersections of the lines 10 and 11 adjacent each of the four corners of the board, there are joining color 60 bands of much greater width than the lines 10 and 11, preferably colored blue, as indicated on the drawing and designated by the reference character 12. These blue lines therefore extend as diagonals of the four 65 corner squares of the board. Along each longitudinal side of the board and connecting the two intermediate intersections of the lines 10 and 11, there is a color band similar to the bands 12 designated by the reference 70 character 13 and preferably colored red as indicated on the drawing. This color band red is extended to connect also the second 75 intersections of the lines 10 and 11 from each corner of the board or intersection of 80 the boundary lines 10, the diagonal portions of the color band 13 being therefore parallel with the color bands 12.

It is preferred in forming my improved game board, after the same is laid off in 85 squares by the intersecting lines 10 and 11, to join all intersections by diagonal lines as illustrated in the drawing, by the diagonal black lines which are not given designating characters. This construction enables the blue and 90 red color bands 12 and 13 to be formed as illustrated in Fig. 1 on the inner periphery of these diagonal lines and on the inside of the boundary lines 10. On the interior of the color band 13 the square formed by the 95 intersection of the diagonal lines joining the centers of the four intermediate squares at each side of the board, is a third color band 100 colored preferably blue or any other desired color like the outer diagonal bands 12 which it parallels, the same being designated by the reference character 14. The diagonal lines joining the centers of the four squares immediately surrounding the center square of the board, are joined with a fourth color 105 band, preferably colored red like the outer color band 12 and designated by the reference character 15. The elongated rectangular spaces lying immediately between the color bands 14 and 15, of a length equal to 110 the bands 15, are colored black or other suitable differentiating color as indicated by the

reference character 16. The center square of the board bounded by the lines 11 and inscribed within the color band square 15, is termed the "home" square, and in order that this center home square may be plainly marked, the interior portions thereof at the corners intersected by the bands 15, may be given a distinguishing color, as indicated at the corners 17, while at the center of the square and at the intersection of the diagonals thereof, there may be a small mark or square similarly colored, as indicated at 18.

The game pieces which I prefer to use in connection with my improved game board, 15 are thirty-six in number and are designated in Figs. 2 to 5 inclusive as being of two colors, as, for example, blue and red. Nine pieces of the color blue are marked with the letter A; nine of the same color are marked with the letter C; nine of the red pieces are marked with the letter B; and nine of the same color are marked with the letter D. These game pieces obviously may be rectangular in form as illustrated or they may be 25 circular in form, or of any other desired form, so that they are properly colored and provided with designating letters or characters as indicated.

The four corners of the board are designated generally by the reference characters A, B, C, and D, and the fields of the board adjacent these corners may be known as field A, field B, field C and field D. The game pieces divided into four groups of nine 30 pieces each are placed on the board, nine at each corner field, as indicated on the drawing adjacent the field A, where, for convenience, I have designated the original positions of the pieces A on the corner field A by squares designated by the reference character *a*. It will be seen that in the field A the nine pieces in blue marked with the designation A will be placed where indicated by the squares *a* at the intersections 35 of the parallel and diagonal lines, and that one of these original positions will fall at the extreme corner A of the board, and three of these positions will be disposed along the blue line 12, with the remaining five positions at the intersections along the red color band 13. In a similar manner, all of the 40 pieces marked B will be placed together at the corner marked B; those marked C at the corner marked C; and those marked D at the field adjacent the corner marked D.

The game can be played by two or four persons. If by two, each player takes a color, if by four persons, each player takes a letter, the two of the same color being 45 partners.

In playing the game, one color takes the other color with regard to the game pieces. The A pieces move first, then B, then C, and then D; then A again and so on in turn. Each player moves one piece at a time one

point. Each intersection of a line is called a point or space and by this is meant intersections of either the boundary lines or diagonals of the original twenty five squares of the board, without regard to the color 70 designations, with the exception that the colored fields 16 are dead spaces and cannot be occupied, but there are points or intersections all around these spaces 16 wherever there is an intersection of a line, which 75 may be occupied. A piece moving from corner A, B, C, or D, cannot move back to that corner but may travel on the first blue line 12 back and forth from one point to another. As soon as it reaches the first red 80 line 13, it cannot move back to the blue line it first left, but can travel all around the board on the red line. Then, after it reaches the second blue line, it cannot move back to the red line just left but may travel all 85 around on that line. At last if it reaches the second red line it may travel to any point in that square but may not move from it. The taking of the pieces takes place in any direction in a straight line, even backward, 90 when a piece of a color stands in front of one of another color not supported from behind, and taking is accomplished by jumping over the piece to be taken and taking the place behind it. Any piece thus moving 95 may take as many pieces as it finds unsupported. Taking is obligatory. When a letter has been all taken off the board, the next in order plays, as, for example, when C is all taken, then D plays, then A, then B, 100 then D, etc. The object of the game is to place in the center square, on the points designated 17 and 18, five pieces of the same color, and the first side accomplishing 105 this wins the game.

In order that the invention might be understood, the details of the preferred embodiment have been shown and particularly described, but it will be apparent that persons skilled in the art may resort to various 110 modifications without departing from the purpose and spirit of the invention, and it is not desired to be limited to the specific embodiment of the invention illustrated and described.

I claim:

1. A game apparatus, consisting of a board provided with a diagram comprising an outer square which is divided into a plurality of inner squares of equal sizes by a plurality of parallel lines also parallel with the sides of the outer square, each of the said inner squares being divided by their diagonals, certain of said diagonals being variously colored or otherwise designated 120 to divide the space within the outer square into a plurality of zones or fields.

2. A game apparatus consisting of a board provided with a diagram comprising an outer square, said outer square being divided 130

into a plurality of inner squares of equal size by lines extending parallel with and intersecting the sides of said outer square, the said inner squares being divided by their diagonals, certain of the said diagonals of the inner squares being colored to divide the board into a plurality of fields.

3. A game apparatus consisting of a board provided with a diagram comprising an outer square and a series of inner squares of uniform size arranged within the outer square by a plurality of dividing lines extending parallel with the sides of the outer square, each of the said equal inner squares being divided by its diagonals, means for designating the intersections of the sides and diagonals of the inner central square of the board, means for designating the square circumscribed about the said inner central square, its sides being bisected by the corners of the said inner central square, and a plurality of fields surrounding the said inner squares being formed by variously colored bands extending along the diagonals of the said inner squares.

4. A game apparatus consisting of a board provided with a diagram comprising an outer square and a series of inner squares of uniform size arranged within the outer square by a plurality of dividing lines extending parallel with the sides of the outer square, each of the said equal inner squares being divided by its diagonals, means for designating the intersections of the sides and diagonals of the inner central square of the board, means for designating the square circumscribed about the said inner central square its sides being bisected by the corners of the said inner central square, a plurality of fields surrounding the said inner squares being formed of variously colored bands extending along the diagonals of the said inner squares, and a plurality of game pieces divided into groups of two color designations and each of said color groups being divided into two groups distinguished by different character designations.

5. A game apparatus consisting of a board provided with a diagram comprising an outer square divided into a plurality of equal inner squares by lines extending parallel with the sides of the said outer square, the corners of the various equal inner squares being connected by diagonal lines, color designations for indicating the central inner square, a color designation for distinguishing the square formed by the diagonals of the squares surrounding the said inner square, a second colored square surrounding the first said colored square being bounded by the diagonals of the next succeeding outer tier of inscribed squares and designated by a different color band from the first said colored square, colored fields bounded by the sides of the two said colored

squares, and outer colored bands surrounding the aforesaid inner colored bands being formed parallel therewith and diagonal lines of the said inscribed squares.

6. A game apparatus consisting of a board provided with a diagram comprising an outer square and a series of inner squares of uniform size formed by dividing lines parallel with and intersecting the sides of the said outer square, the corners of the said inscribed squares being connected by their diagonal lines, certain of the said diagonal lines being variously colored to designate various fields within the said outer square.

7. A game apparatus consisting of a board provided with a diagram comprising an outer square and a series of inner squares of uniform size formed by dividing lines parallel with the sides of the said outer square, the corners of the said inscribed squares being connected by their diagonal lines, certain of the said diagonal lines being variously colored to designate various fields within the said outer square, and a plurality of game pieces adapted to be used in conjunction with said board and consisting of two groups of pieces each group provided with different distinguishing colors and each group being divided into two equal groups by character designations.

8. A game apparatus consisting of a board provided with a diagram comprising an outer square being divided into a plurality of equal inner squares by division lines extending parallel with the sides of the outer square, each of the said inner squares being provided with bisecting diagonal lines, means for designating the central square, means for designating the square circumscribed around the central square of the board which coincides with the diagonals of the square surrounding the said central square, a color band formed coincidently with the square formed by the diagonals of the squares contiguous to the four corners of the central square and extending into adjacent squares, and other color bands distinguished from the aforesaid color bands by different color designations and being formed along the progressive diagonals of the squares toward the outer edge of the board and parallel with the said inner color bands.

9. A game apparatus consisting of a board provided with a diagram comprising an outer square being divided into a series of inner squares of uniform size by a plurality of lines parallel with and intersecting the sides of the outer squares, the said inner squares being divided each by its intersecting diagonal lines, and color designations for indicating the intersections of each of the lines forming the inner squares and the diagonals thereof, the said color designations being extended in the form of bands

coinciding with the parallel diagonals of the inner squares.

10. A game apparatus consisting of a board provided with a diagram comprising an outer square being divided into a series of inner squares of uniform size by a plurality of lines parallel with the sides of the outer square, the said inner squares being divided each by its intersecting diagonal lines, color designations for indicating the intersections of each of the lines forming the inner squares and the diagonals thereof, the said color designations being extended

in the form of bands coinciding with the parallel diagonals of the inner squares, and 15 color fields interposed between certain of the said color band diagonals.

In testimony whereof I have signed my name to this specification, in the presence of two subscribing witnesses, on this 19th day 20 of January, A. D. 1915.

MAXIMILIEN MARIS.
